HOWARD A. THOMPSON, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL SIGNALING

Application filed July 19, 1930. Serial No. 469,241.

My invention relates to electrical signaling apparatus, and particularly to apparatus for indicating the length of a train.

I will describe one form of apparatus embodying my invention, and will then point out the novel features thereof in claims.

The accompanying drawing is a diagrammatic view illustrating one form of electrical signaling apparatus embodying my invention.

Referring to the drawing, the reference characters 1 and 1^a designate the track rails of a stretch of railway track over which traffic normally moves in the direction indicated by the arrow. Track rail 1^a is divided, by means of insulated joints 2, to form two adjacent track sections A—C and C—F. Track circuit current is supplied to the rails of each track section from a track transformer, designated by the reference character T with a suitable exponent, and having its secondary connected across the rails adjacent the exit end of the corresponding section in series with the usual current limiting impedance.

The primary of each transformer T is supplied with alternating current from the terminals X and Y of a suitable source of current not shown in the drawing. Each track section is also provided with a track relay, designated by the reference character R with a suitable exponent, and comprising two windings 3 and 4, one of which, 3, is constantly connected across the rails adjacent the entrance end of the corresponding section. The other winding 4 of each track relay is constantly supplied with alternating current from terminals X and Y, so that when track circuit current is supplied to winding 3 of the relay from the rails of the corresponding section, the track relay is energized.

An insulated joint 5^B is located in rail 1^a of section A—C at a point B which is a comparatively short distance, for example one rail length, in rear of the exit end of this section. Two other insulated joints 5^D and 5^E are located in rail 1^a of section C—F at the points D and E, respectively. The points D and E may be spaced from the entrance end of section C—F any suitable distances but, for purposes of explanation I will assume

that the point D is spaced from the entrance end of section C—F a distance corresponding to the length of a train composed of six cars, while the point E is spaced from the entrance end of section C—F a distance which corresponds to the length of a train composed of ten cars.

Associated with each of the joints 5 is an auxiliary relay, designated by the reference character G with an exponent corresponding to the location.

Each relay G is intended to be operated in response to the difference in potential existing between the confronting ends of rail 1^a at the associated joint 5 when the section in which the joint is included is unoccupied between such joint and the exit end of the section.

To this end, each relay, as here shown, is connected through a full wave rectifier 8 with the secondary 6 of a transformer, designated by the reference character J with a suitable distinguishing exponent, and having its primary 7 connected with the rails on opposite sides of the corresponding joint 5.

With this arrangement, it will be plain that the alternating current supplied to the rails of section A—C from track transformer T^C normally flows through the rails of this section in series and through winding 3 of track relay R^A and primary 7 of

transformer J^B. Similarly, the alternating current supplied to the rails of section C—F by track transformer T^F normally flows through the rails of this section in series and through the winding 3 of track relay R^C and the primary 7 of each of the transformers J^D and J^E.

The alternating current thus supplied to each transformer J energizes the associated relay G.

The track relay R^C and the auxiliary relay G control three stick relays H¹, H² and H³. Relay H¹ is provided with a pick-up circuit which passes from terminal X through back contact 9 of track relay R^C, front contact 10 of auxiliary relay G^B, front contact 11—11^a of auxiliary relay G^D, and winding of relay H¹ to terminal Y.

Relay H¹ is also provided with a stick circuit which passes from terminal X through back contact 9 of track relay R^C, front contact 12 of relay H¹, and the winding of relay H¹ to terminal

100

Y. Relay H^2 is provided with a pick-up circuit which passes from terminal X through back contact 9 of track relay R^c , front contact 10 of relay G^p , back contact 11-11^b of relay G^p , front contact 13-13^a of relay G^p , and winding of relay H^2 to terminal Y. Relay H^2 is also provided with a stick circuit which passes from terminal X through back contact 9 of track relay R^c , front contact 14 of relay H^2 , and winding of relay H^2 to terminal Y. Relay H^3 is provided with a pick-up circuit which passes from terminal X through back contact 9 of track relay R^c , front contact 10 of auxiliary relay G^p , back contact 11-11^b of auxiliary relay G^p , back contact 13-13^b of auxiliary relay G^p , and winding of relay H^3 to terminal Y. Relay H^3 is also provided with a stick circuit which passes from terminal X through back contact 9 of track relay R^c , front contact 15 of relay H^3 , and winding of relay H^3 to terminal Y.

The relays H^1 , H^2 and H^3 , in turn, control three indicating devices, here shown as electric lamps, and designated by the reference characters L^1 , L^2 and L^3 , respectively. These lamps will usually be located at a remote point, as in a signal tower or train despatcher's office. Lamp L^1 is provided with a circuit which passes from terminal X through front contact 16-16^a of relay H^1 and the filament of lamp L^1 to terminal Y. Lamp L^2 is provided with a circuit which passes from terminal X through back contact 16-16^b of relay H^1 , front contact 17-17^a of relay H^2 , and the filament of lamp L^2 to terminal Y. The lamp L^3 is provided with a circuit which passes from terminal X through back contact 16-16^b of relay H^1 , back contact 17-17^b of relay H^2 , front contact 18 of relay H^3 , and the filament of lamp L^3 to terminal Y.

As shown in the drawing, section A-C and C-F are both unoccupied. The relays G are therefore all energized. Track relay R^c is also energized. Relays H^1 , H^2 and H^3 are therefore all deenergized, and the lamps L^1 , L^2 and L^3 are all extinguished.

In explaining the operation of the apparatus, I will first assume that a train which is moving in the direction of the arrow, and which is shorter than the distance from the point C to the point D traverses the stretch of track illustrated in the drawing. As soon as the front end of the train passes point B, current from track transformer T^c will be shunted away from the primary 7 of transformer J^b , and relay G^p will therefore become deenergized. This relay will then remain deenergized until the rear end of the train has passed point C. As long as relay G^p is deenergized, the pick-up circuits for relays H^1 , H^2 and H^3 are open at front contact 10 of this relay, and it will be apparent, therefore, that none of the relays H^1 , H^2 and H^3

can become energized while any portion of the train occupies portion B-C of section A-C. When the train enters section C-F, current will be shunted away from winding 3 of track relay R^c , and track relay R^c will become deenergized, and will close its back contact 9. This has no effect on the remainder of the apparatus, however, until the rear of the train passes out of section A-C, whereupon relay G^p picks up and closes its front contact 10. Since the train is shorter than the distance from the point C to the point D, relay G^p is energized, so that when relay G^p becomes energized, the pick-up circuit for relay H^1 will become closed, and relay H^1 will become energized. The closing of front contact 16-16^a of relay H^1 completes the circuit for lamp L^1 , and this lamp therefore becomes lighted to indicate that the train which has just entered section C-F is shorter than the distance from the point C to the point D. When the front end of the train passes point D, relay G^p , will become deenergized and will open its front contact 11-11^a and close its back contact 11-11^b. The opening of front contact 11-11^a of relay G^p interrupts the pick-up circuit for relay H^1 , but relay H^1 remains energized by virtue of the stick circuit previously traced for this relay which is then closed at front contact 12 of this relay. The closing of back contact 11-11^b of relay G^p completes the pick-up circuit for relay H^2 , and relay H^2 , becomes energized and closes its stick circuit. This has no effect on the remainder of the apparatus under these conditions, however, since the circuits for the lamps L^1 and L^2 are now both open at back contact 16-16^b of relay H^1 . Likewise, when the front end of the train passes point E, relay G^p will become deenergized, thereby completing the pick-up circuit for relay H^3 so that this latter relay will become energized and will close its stick circuit. This also has no effect on the remainder of the apparatus under these conditions, however, due to the circuits for the lamps L^2 and L^3 being open at back contact 16-16^b of relay H^1 .

When the train has passed completely out of section C-F, current will again be supplied to winding 3 of track relay R^c and to the relays G^p and G^e , so that track relay R^c and relays G^p and G^e will again become energized. When back contact 9 of relay R^c opens, all of the circuits for the relays H^1 , H^2 and H^3 are interrupted, and these relays therefore become deenergized. Lamp L^1 then becomes extinguished. The apparatus is then restored to its normal condition in which it is illustrated in the drawing.

I will now assume that a train which is longer than the distance from the point C to the point D, but which is shorter than the distance from the point C to the point E traverses, in the direction of the arrow, the

stretch of track illustrated in the drawing. As soon as the front end of the train passes point B, relay G^B will become deenergized as explained above, but under these conditions, 5 before this relay again becomes energized due to the rear end of the train having passed point C, the front end of the train will have passed point D but not point E. As a result, when front contact 10 of relay G^B now becomes closed, it completes the pick-up circuit for relay H^2 , and relay H^2 becomes energized. Relay H^1 is deenergized under these conditions, since its pick-up circuit is open at front contact 11-11^a of relay G^B , 15 and lamp L^2 therefore becomes lighted to indicate that the train in section C-G is longer than the distance from the point C to the point D, but is shorter than the distance from the point C to the point E. When 20 the front end of the train passes point E, relay G^E will become deenergized, and will open its front contact 13-13^a and close its back contact 13-13^b. When front contact 13-13^a of relay G^E is opened, the pick-up 25 circuit previously traced for relay H^2 is opened at this contact but relay H^2 remains energized due to its stick circuit which is now closed at its front contact 14. When back contact 13-13^b of relay G^E is closed, the pick-up circuit for relay H^3 is closed, and this relay becomes energized and closes its stick circuit but since the circuit for lamp L^3 30 is then open at back contact 17-17^a of relay H^2 , the energization of relay H^3 does not affect the remainder of the apparatus. When 35 the train has completely passed out of section C-F, winding 3 of relay R^C and relays G^D and G^E will all become energized. When winding 3 of relay R^C becomes energized, it 40 opens its back contact 9, thereby deenergizing relays H^2 and H^3 . The lamp L^2 then becomes extinguished and the parts are restored to their normal conditions.

If a train which is longer than the distance 45 from the point C to the point E traverses the stretch of track illustrated in the drawing, then when the rear end of the train has cleared section A-C, winding 3 of track relay R^C as well as relays G^D and G^E will all be deenergized. As a result, when relay G^B becomes energized and closes its front contact 10 under these conditions, the pick-up circuit for relay H^3 will be completed, and 55 relay H^3 will therefore become energized and will close its stick circuit. Relays H^1 and H^2 are then both deenergized, and lamp L^3 therefore becomes lighted to indicate that the train is longer than the distance from 60 the point C to the point E. When the train has completely cleared section C-F, winding 3 of track relay R^C and relays G^D and G^E will again become energized. Relay H^3 will therefore become deenergized and will extinguish lamp L^3 . All parts are then re-

stored to their normal conditions in which they are illustrated in the drawing.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a first contact, means for operating said first contact when the front end of a train passes a first point along the trackway and for subsequently maintaining said first contact in its operated condition until the train has passed beyond a second point along the trackway in advance of said first point, a second contact, means for operating said second contact when the front end of the train passes said second point and for subsequently maintaining said second contact in its operated condition until the train has passed beyond a third point along the trackway located in advance of said second point, a third contact, means for operating said third contact when the front end of the train passes a fourth point along the trackway located between said second and third points and for subsequently maintaining said third contact in its operated condition until said train has passed beyond said third point; a relay controlled by said first, second, and third contacts in such manner that said relay becomes energized when said first contact is in its unoperated condition and said second and third contacts are in their operated conditions, and indication means controlled by said relay.

2. In combination, a first contact, means for operating said first contact when the front end of a train passes a first point along the trackway and for subsequently maintaining said first contact in its operated condition until the train has passed beyond a second point along the trackway in advance of said first point, a second contact, means for operating said second contact when front end of the train passes said second point and for subsequently maintaining said second contact in its operated condition until the train has passed beyond a third point along the trackway located in advance of said second point, a third contact, means for operating said third contact when the front end of the train passes a fourth point along the trackway located between said second and third points and for subsequently maintaining said third contact in its operated condition until said train has passed beyond said third point; a relay controlled by said first, second, and third contacts in such manner that said relay becomes energized when said first and said third contacts are in their unoperated condition and

said second contact is in its operated condition, and indication means controlled by said relay.

3. In combination, a first normally closed contact, means for opening said first normally closed contact when the front end of a train passes a first point along the trackway and for subsequently holding said first normally closed contact open until the train has 10 passed beyond a second point along the trackway located in advance of said first point, a normally open contact, means for closing said normally open contact when the front end of the train passes said second point and for 15 subsequently holding said normally open contact closed until the train has passed beyond a third point along the trackway located in advance of said second point, a second normally closed contact, means for opening 20 said second normally closed contact when the front end of the train passes a fourth point along the trackway located between said second and third points and for subsequently holding said second normally closed contact open until the train has passed beyond said third point, a relay controlled by said three contacts, and means controlled by said relay 25 for indicating whether a train occupying said stretch is longer or shorter than the distance between said second and fourth points.

4. In combination, a first normally closed contact, means for opening said first normally closed contact when the front end of a train passes a first point along the trackway 35 and for subsequently holding said first normally closed contact open until the train has passed beyond a second point along the trackway located in advance of said first point, a normally open contact, means for closing said 40 normally open contact when the front end of the train passes said second point and for subsequently holding said normally open contact closed until the train has passed beyond a third point along the trackway located in advance of said second point, a second normally closed contact, means for opening said second normally closed contact when the front end of the train passes a fourth point along the trackway located between said second and said third points and for subsequently holding said second normally closed contact open until the train has passed beyond said third point, a relay, a pick-up circuit for said relay including said three contacts, a stick circuit for said relay including said normally open contact and a front contact of said relay, and indication means controlled by said relay.

5. In combination, a first normally closed contact, means for opening said first normally closed contact when the front end of a train passes a first point along the trackway and for subsequently holding said first normally closed contact open until the train 135 has passed beyond a second point along the

trackway located in advance of said first point, a first normally open contact, means for closing said first normally open contact when the front end of the train passes said second point and for subsequently holding said first normally open contact closed until the train has passed beyond a third point along the trackway located in advance of said second point, a second normally closed contact and a second normally open contact, means for opening said second normally closed contact and for closing said second normally open contact when the front end of the train passes a fourth point along the trackway located between said second and third points and for subsequently holding said second normally closed contact open and said second normally open contact closed until the train has passed beyond said third point, two relays, a pick-up circuit for one of said relays including said first and second normally closed contacts and said first normally open contact, a stick circuit for said one relay including said first normally open contact and a front contact of said one relay, a pick-up circuit for the other relay including said first and second normally open contacts as well as said first normally closed contact, a stick circuit for said other relay including said first normally open contact and a front contact of said other relay, and indication means selectively controlled by said relays.

6. In combination, a first normally closed contact, means for opening said first normally closed contact when the front end of a train passes a first point along the trackway and for subsequently holding said first normally closed contact open until the train has passed beyond a second point along the trackway located in advance of said first point, a first normally open contact, means for closing said first normally open contact when the front end of the train passes said second point and for subsequently holding said first normally open contact closed until the train has passed beyond a third point along the trackway located in advance of said second point, a second normally closed contact and a second normally open contact, means for opening said second normally closed contact and for closing said second normally open contact when the front end of the train passes a fourth point along the trackway located between said second and third points and for subsequently holding said second normally closed contact open and said second normally open contact closed until the train has passed beyond said third point, a third normally closed contact and a third normally open contact, means for opening said third normally closed contact and for closing said third normally open contact when the front end of the train passes a fifth point along the trackway located between said fourth and said third points and for 120

said second, third, and fourth relays are all deenergized and said first relay is energized; and indication means selectively controlled by said fifth, sixth and seventh relays.

- 5 9. In combination, four normally energized relays, means for deenergizing a first one of said relays when the front end of a train passes a predetermined point along the trackway and for subsequently maintaining said first relay in its deenergized condition until the train has passed beyond a second point along the trackway located in advance of said first point, means for deenergizing a second one of said relays when 10 the front end of the train passes said second point and for subsequently maintaining said second relay in its deenergized condition until the train has passed beyond a third point along the trackway located in advance 15 of said second point, means for deenergizing a third one of said relays when the front end of the train passes a fourth point along the trackway located between said second and third points and for subsequently maintaining 20 said third relay in its deenergized condition until the train has passed beyond said third point, means for deenergizing a fourth one of said relays when the front end of the train passes a fifth point along the trackway 25 located between said fourth and said third points and for subsequently maintaining said fourth relay in its deenergized condition until the train has passed beyond said third point, a fifth, a sixth, and a seventh 30 relay; a pick-up circuit for said fifth relay including a back contact of said second relay, a front contact of said first relay, and a front contact of said third relay; a stick circuit for said fifth relay including said back contact of said second relay and a front contact of said fifth relay; a pick-up circuit for 35 said sixth relay including said back contact of said second relay, said front contact of said first relay, a back contact of said third relay, and a front contact of said fourth relay; a pick-up circuit for said seventh relay including said back contact of said second relay, said front contact of said first relay, said back contact of said third relay, and a back contact of said fourth relay; a stick circuit for 40 said seventh relay including said back contact of said second relay and a front contact of said seventh relay; three indicating devices, a circuit for a first one of said devices including a front contact of said fifth relay, a circuit for a second one of said devices including a back contact of said fifth relay and a front contact of said sixth relay; and a circuit for the remaining one of said indicating devices including said back contact of said fifth relay, a back contact of said 45
- 50
- 55
- 60
- 65

sixth relay, and a front contact of said seventh relay.

10 10. In combination, a section of railway track, a source of energy connected across the rails adjacent the exit end of the section, a track relay connected across the rails adjacent the entrance end of the section, two insulated joints in one rail located at spaced points intermediate the ends of such section, two windings one connected across each of 10 said joints, and means controlled by said track relay and by said two windings and effective when and only when a train has completely entered said section for indicating the length of said train. 15

11 11. In combination, a section of railway track, a source of energy connected across the rails adjacent the exit end of the section, a track relay connected across the rails adjacent the entrance end of the section, a first insulated joint in one rail located intermediate the ends of said section, a second insulated joint in one rail located intermediate the ends of the section, in advance of 20 said first joint, two windings one connected across each of said insulated joints, a contact, means for operating said contact when the front end of a train passes a point along the trackway in rear of the entrance end of 25 said section and for subsequently maintaining said contact in its operated condition until the train has completely entered said section; and means controlled jointly by said contact, said two windings, and said relay for indicating whether a train occupying 30 said section is shorter than the distance from the entrance end of said section to said first joint, or is longer than the distance from the entrance end of said first section to said first joint but shorter than the distance from the 35 entrance end of said section to said second joint, or is longer than the distance from the entrance end of said section to said second joint. 40

12 12. In combination, a section of railway track, a source of energy connected across the rails adjacent the exit end of the section, a track relay connected across the rails adjacent the entrance end of the section, an insulated joint in one rail of said section located in advance of the entrance end of the section, a transformer having its primary connected across said joint, a second relay at times receiving energy from said transformer, a contact, means for operating said contact when the front end of a train passes a point along the trackway in rear of the entrance end of said section and for subsequently maintaining said contact in its operated condition until the train has completely entered said section, a third relay; means for energizing said third relay when said track relay is deenergized, said second relay is energized, and said contact is in its unoper- 45

ated condition; and an indicating device controlled by said third relay.

13. In combination, a section of railway track, a source of energy connected across the rails adjacent the exit end of the section, a track relay connected across the rails adjacent the entrance end of the section, an insulated joint in one rail of said section located in advance of the entrance end of the section, a transformer having its primary connected across said joint, a second relay at times receiving energy from said transformer, a contact, means for operating said contact when the front end of a train passes a point along the trackway in rear of the entrance end of said section and for subsequently maintaining said contact in its operated condition until the train has completely entered said section, a third and a fourth relay; means for energizing said third relay when said track relay is deenergized, said second relay is energized, and said contact is in its unoperated condition; means for energizing said fourth relay when said track relay and said second relay are both deenergized and said contact is in its unoperated condition, and indicating devices selectively controlled by said third and fourth relays.

14. In combination, a section of railway track, a source of energy connected across the rails adjacent the exit end of the section, a track relay connected across the rails adjacent the entrance end of the section, a first insulated joint in one rail of the section in advance of the entrance end of the section, a second insulated joint in said one rail of the section in advance of said first joint, a first transformer having its primary connected across said first insulated joint, a second transformer having its primary connected across said second insulated joint, a second relay at times receiving energy from said first transformer, a third relay at times receiving energy from said second transformer, a normally closed contact, means for opening said contact when the front end of a train passes a point along the trackway in rear of the entrance end of said section and for subsequently holding said contact open until the train has completely entered said section, a fourth, a fifth, and a sixth relay; a pick-up circuit for said fourth relay including a back contact of said track relay, said normally closed contact, and a front contact of said second relay; a stick circuit for said fourth relay including said back contact of said track relay and a front contact of said fourth relay; a pick-up circuit for said fifth relay including said back contact of said track relay, said normally closed contact, a back contact of said second relay, and a front contact of said third relay; a stick circuit for said fifth relay including said back contact of said track relay and a front contact of said fifth relay; a pick-up

circuit for said sixth relay including said back contact of said track relay, said normally closed contact, said back contact of said second relay, and a back contact of said third relay; a stick circuit for said sixth relay including said back contact of said track relay and a front contact of said sixth relay; and indication means selectively controlled by said fourth, fifth, and sixth relays.

15. In combination, two adjacent sections of railway track, two sources of energy one connected across the rails adjacent the exit end of each section, a first insulated joint in one rail located intermediate the ends of the forward one of said sections, a second insulated joint in one rail located intermediate the ends of the rear one of said sections, two windings one connected across each said joint, and means controlled partly by both said windings for indicating whether a train occupying said forward section is longer or shorter than the distance from the entrance end of the forward section to said first insulated joint.

16. In combination, two adjacent sections of railway track, two sources of energy one connected across the rails adjacent the exit end of each section, a track relay connected across the rails adjacent the entrance end of the forward one of said sections, a first insulated joint in one rail located intermediate the ends of said forward section, a second insulated joint in one rail located intermediate the ends of the rear one of said sections, two windings one connected across each said joint, and means controlled by both said windings and by said track relay for indicating whether a train occupying said forward section is longer or shorter than the distance from the entrance end of said forward section to said first insulated joint.

17. In combination, two adjacent sections of railway track, two sources of energy one connected across the rails adjacent the exit end of each section, a track relay connected across the rails adjacent the entrance end of the forward one of said sections, a first insulated joint in one rail located intermediate the ends of said forward section, a second insulated joint in one rail located intermediate the ends of the rear one of said sections, a first transformer having its primary connected across said first insulated joint, a second relay receiving energy from said first transformer, a second transformer having its primary connected across said second insulated joint, a third relay receiving energy from said second transformer, and means controlled by said track relay and by said second and third relays, for indicating whether a train occupying said forward section is longer or shorter than the distance from the entrance end of said forward section to said first insulated joint.

18. In combination, two adjacent sections

- of railway track, two sources of energy one connected across the rails adjacent the exit end of each section, a track relay connected across the rails adjacent the entrance end of 5 the forward one of said sections, a first insulated joint in one rail located intermediate the ends of said forward section, a second insulated joint in one rail located intermediate the ends of the rear one of said sections, a first 10 transformer having its primary connected across said first insulated joint, a first rectifier, a second relay connected with the secondary of said first transformer through said first rectifier, a second transformer having its 15 primary connected across said second insulated joint, a second rectifier, a third relay connected with the secondary of said second transformer through said second rectifier, and means controlled by said track relay and 20 by said second and third relays, for indicating whether a train occupying said forward section is longer or shorter than the distance from the entrance end of said forward section to said first insulated joint.
- 25 19. In combination, a section of railway track, a source of energy connected across the rails adjacent one end of said section, a track relay connected across the rails adjacent the other end of said section, an insulated 30 joint in one rail of said section, a winding connected across said joint, and means controlled by said track relay and by said winding for indicating the length of a train entering said section.
- 35 20. In combination, a section of railway track, a source of energy connected across the rails adjacent one end of said section, a track relay connected across the rails adjacent the other end of said section, an insulated 40 joint in one rail of said section, a winding connected across said joint, a stick relay controlled by said track relay and by said winding, and means controlled by said stick relay for indicating the length of a train entering said section.

In testimony whereof I affix my signature.
HOWARD A. THOMPSON.
